UNITED STATES PATENT OFFICE.

WILLIAM P. DAY, OF CLEVELAND HEIGHTS, OHIO.

SHOCK ABSORBER.

Application filed October 1, 1926. Serial No. 138,976.

This invention relates generally to shock absorbers employed in connection with automobiles to restrain or relieve the rapid rebound of the vehicle and its axle.

5 The object of the invention is to provide an exceedingly simple, inexpensive and efficient device which can be quickly and easily attached to automotive vehicles in use and which will effectively retard the return 10 movement of the parts and thereby avoid the disagreeable shock or bump which would otherwise occur in the passage of the vehicle over uneven ground.

With these objects in view the invention 15 consists in the novel features of construction and in the manner of combining and arranging the same all of which will be described hereinafter and set forth in the appended claims.

20 In the drawing forming part of this specification, Fig. 1 is a view showing the practical operation of my invention, the cover being removed; Fig. 2 is a vertical longitudinal sectional view; Fig. 3 is a transverse 25 sectional view on the line 3-3 of Fig. 2; and Fig. 4 is a sectional elevation.

In carrying out my invention, I employ a back plate or casting A which is connected to the member B of the motor vehicle frame, said back plate or casting being preferably 30 constructed with an inwardly projecting lug A' which is adapted to rest upon the member B and this casting or plate A is also provided with a boss A² through which a fastening bolt is passed for the purpose of rigidly securing the casting or plate A to the vehicle frame. This plate or casting A is 35 preferably circular in shape and connected thereto at its center is an outwardly projecting post or bolt C which may be formed with an enlargement C' intermediate its ends and connected to this cylindrical enlargement is the inner end of a convolute spring D, this spring being coiled a number 40 of times around said centrally disposed post or bolt and at its free end is connected to a clevis E and to this clevis E is connected the upper end of a strap F preferably of fabric but it will of course be understood that the 45 strap may be of any suitable material. The lower end of the strap is connected to a clevis G which in turn is rigidly connected to the front axle H. The convolute spring

is contained within a cylindrical shaped casing I composed of two similar longitudinal sections, said sectional casing turning freely upon the central post or bolt and is 55 preferably provided with bushings I'.

A spacing collar or washer I² is preferably interposed between the inner side of the cylindrical casing and the plate or casting A and a nut I³ screwed upon the threaded portion of the post or bolt serve to hold the two longitudinal sections of the cylindrical casing together, a washer I⁴ being interposed 60 between the nut and outer side of the casing. The clevis E projects through notches cut in the opposed edges of the sections of the cylindrical casing.

65 By having one end of the strap connected to the end of the spring and the other end of the strap connected to the axle of the vehicle, it is obvious that when the vehicle body moves toward said axle, the tension of the spring will tend to take up the slack 70 in the strap and on the rebound the strap will pull against the spring and tend to wind the same upon the central post or bolt and at the same time the cylindrical casing 75 will be caused to turn an amount equal to the movement of the clevis inasmuch as the said clevis projects outwardly from the cylindrical surface of the casing resting in notches and consequently when the clevis is moved the cylindrical casing must necessarily 80 turn with it.

85 In order to prevent too sudden a return movement or in other words to absorb the shock on the rebound, I employ a brake shoe K pivoted at K' to the back plate or casting and having a leather or fabric face K² which contacts with the cylindrical surface of the casing I. In practice the brake shoe K is carried between parallel side members K³ and rollers K⁴ are arranged at each 90 end of these parallel members at opposite ends of the brake shoe K, the strap F passing over and contacting with these rollers and brake shoe serves to hold the face of the brake shoe in contact with the cylindrical 95 surface of the casing and owing to the relative positions of the strap ends and the brake shoe, it will be noted that upon the rebound the initial tension is placed upon the brake shoe applying a brake to the exterior of the 100 drum at the same time that the convolute 105

spring is exerting tension upon the opposite end of the strap. In this manner the rebound or return movement is materially retarded and the action of the device materially improved.

I have shown the brake shoe pivoted at K' at the point about 60° above the horizontal but it will be understood that it can be arranged at other points and for the purpose 10 of adjustment the back plate or casting is provided with a plurality of bolt openings K⁵ to accommodate the pivot bolt of the brake shoe. If desired a housing L of thin sheet metal may be employed to enclose the 15 operating parts of the device and when such a shell or housing is employed it is provided with a central opening through which the outer end of the central bolt or stud C projects and upon which a fastening nut and 20 washer may be secured. The use of a convolute spring and cylindrical casing with a strap wound thereon has been employed but it has been found that there is not sufficient retardation in the operation during the 25 rebound and consequently with the object of providing the proper retardation at all times, I have devised the curved brake shoe and arrange the same in the manner set forth relatively with respect to the cylindrical 30 casing and the tension of the connecting strap and by so doing provide for the proper retardation but at the same time permitting the free and gradual return of the parts to their normal positions through the rebounding action.

The parts are of such a simple nature that there is nothing to get out of order and they can be quickly and easily assembled and when once installed need no further adjustment, depending as they do upon their relative positions for the correct and efficient operation of all of the parts.

Having thus described my invention, what I claim is:—

45 1. In a shock absorber, the combination with a strap, of a back plate, of a cylindrical casing carried by said back plate and containing a convolute spring, one end of said strap being connected to said convolute spring, the other end of said strap being connected to the vehicle axle, and a brake shoe pivotally secured to said back plate and arranged between the cylindrical casing and strap and adapted to be brought into frictional engagement with said cylindrical casing by said strap as set forth.

50 2. In a shock absorber, the combination with a back plate, of a rotatable cylindrical casing carried by said back plate and containing a convolute spring the inner end of which is rigidly mounted within said casing, of a strap connected at its upper end to the outer end of said spring the lower end of said strap being connected to the vehicle 55 axle, and a brake shoe pivotally secured to

said casing and arranged in proximity to the cylindrical surface of the casing and adapted to be brought into frictional contact with said casing by tension of said strap.

3. In a shock absorber the combination 70 with a back plate or casting having an outwardly projecting stud or post, a rotatable cylindrical casing arranged upon said stud or post, a convolute spring contained within said cylindrical casing the inner end of said spring being rigidly connected to the stud or post, a strap connected at its upper end to the outer end of said convolute spring the lower end of said strap being connected to the axle of the vehicle, a curved brake 75 shoe pivotally mounted on said back plate and interposed between the cylindrical surface of the casing and the strap, said brake shoe being brought into frictional contact with the cylindrical casing by the tension of 80 the strap.

4. In a shock absorber the combination 90 with a casting having a spring actuated rotatable casing mounted thereon, of a strap connected at its upper end to said casing and at its lower end to the vehicle axle, and a brake shoe pivotally and adjustably connected with said casting and interposed between the cylindrical surface of the casing and said strap and adapted to be brought 95 into frictional contact with the casing by the tension of the strap.

5. In a shock absorber the combination 100 with a casting having a spring actuated cylindrical casing mounted thereon, of a strap connected at its upper end with said casing and at its lower end with the vehicle axle, a brake shoe having one end pivotally secured to said casting and interposed 105 between the cylindrical casing and the strap, said brake shoe being so positioned with reference to the ends of the strap and the cylindrical casing that said brake shoe will be forced into frictional contact with the cylindrical surface of the casing upon the rebound movement of the parts and whereby the proper retardation of the parts during 110 such rebound movement is affected.

6. In a shock absorber the combination 115 with a back plate or casting having an outwardly projecting stud or post, of a two-piece cylindrical casing arranged upon said stud or post, a convolute spring contained within the casing, the inner end of said spring being rigidly connected to the stud or post, a strap having its upper end extending partly around the cylindrical casing, its lower end being connected with the vehicle axle and a clevis connecting the upper end of the strap with the outer end of the convolute spring, and a brake shoe pivotally secured to said casting and interposed between the cylindrical surface of the casing and the strap, said brake shoe being 120 adapted to be brought into frictional contact 125 130

with the cylindrical surface of the casing by the tension upon the strap during the rebound movement.

7. In a shock absorber the combination 5 with a back plate or casting having an outwardly projecting post or stud, of a cylindrical casing rotatably mounted upon said post or stud, a convolute spring arranged within the casing and having its inner end 10 rigidly connected to the post or stud, a strap having its lower end connected with the vehicle axle, the upper portion of said strap extending partly around the cylindrical casing, the upper end of said strap being connected with the outer end of the convolute 15 spring and a curved brake shoe pivotally and adjustably connected to the back plate or casting and adjacent to the cylindrical

casing, the upper portion of the strap contacting with said brake shoe and adapted to 20 force said brake shoe into frictional contact with the cylindrical surface of the casing upon the rebound movements of the vehicle and axle.

8. A shock absorber as set forth in claim 25 1 in which said brake shoe is provided with one or more rollers over which said strap extends.

9. A shock absorber as set forth in claim 5 30 in which said brake shoe is provided with one or more rollers over which said strap extends.

In testimony whereof, I hereunto affix my signature.

WILLIAM P. DAY.
